(57) **CLAIM**

The ornamental design for a flowable syringe, as shown and described.

DESCRIPTION

FIG. 1 is a top perspective view of a flowable syringe in accordance with the present disclosure;

FIG. 2 is a front plan view of the flowable syringe of FIG. 1; FIG. 3 is a rear plan view of the flowable syringe of FIG. 1; FIG. 4 is a top plan view of the flowable syringe of FIG. 1; FIG. 5 is a bottom plan view of the flowable syringe of FIG. 1; and,

FIG. 6 is a side view of the flowable syringe of FIG. 1, the opposite side view a mirror image.

The broken lines shown in the figures represent portions of the flowable syringe that form no part of the claimed design.
